Primary Examiner — Mimosa De

(57) **CLAIM**

I claim the ornamental design for a chair, as shown and as described.

DESCRIPTION

FIG. 1 is a perspective view taken from the front and one side of a second embodiment of a chair showing the design with the head rest in the contracted position and the arms in the downward position;

FIG. 2 is a right side view thereof;

FIG. 3 is a left side view thereof;

FIG. 4 is a perspective view taken from the rear and one side thereof;

FIG. 5 is a front elevational view thereof;

FIG. 6 is a rear elevational view thereof;

FIG. 7 is a top plan view thereof;

FIG. 8 is a right side view thereof with the head rest in the extended position;

FIG. 9 is a front view thereof with the head rest in the extended position;

FIG. 10 is a right side view thereof with the head rest in the contracted position and the arm rest in the upward position; and,

FIG. 11 is a front view thereof with the head rest in the contracted position and the arm rest in the upward position.

1 Claim, 11 Drawing Sheets
